US0D1022101S

(12) **United States Design Patent** (10) Patent No.: **US D1,022,101 S**
(45) Date of Patent: ** Apr. 9, 2024

(54) **TRAMPOLINE RAMP ASSEMBLY**

(71) Applicant: **Mortrad Ltd.**, Devon (GB)

(72) Inventor: **Jonathan Paul Kay**, Devon (GB)

(73) Assignee: **Mortrad Ltd.** (GB)

(**) Term: **15 Years**

(21) Appl. No.: **29/799,154**

(22) Filed: **Jul. 13, 2021**

(51) LOC (14) Cl. **21-03**

(52) U.S. Cl.

USPC **D21/826**

(58) **Field of Classification Search**

(57) **CLAIM**

The ornamental design for a trampoline ramp assembly, as shown and described.

DESCRIPTION

FIG. 1 is a perspective view of a trampoline ramp assembly, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

1 Claim, 4 Drawing Sheets
